UNITED STATES PATENT OFFICE.

BENJAMIN R. COLEMAN AND LEROY B. TAYLOR, OF CHICAGO, ILLINOIS.

WINDOW CONSTRUCTION.

1,267,746.

Specification of Letters Patent. Patented May 28, 1918.

Application filed March 24, 1915. Serial No. 16,609.

To all whom it may concern:

Be it known that we, BENJAMIN R. COLEMAN and LEROY B. TAYLOR, citizens of the United States, residing at Chicago, in the county of Cook and State of Illinois, have invented a certain new and useful Improvement in Window Constructions, of which the following is a full, clear, concise, and exact description, reference being had to the accompanying drawings, forming a part of this specification.

Our invention relates to window constructions and especially to a window construction in which the window sash may be swung or moved outwardly instead of being slid longitudinally of the window frame.

Prominent objects of the invention are to provide a simple, practical and effective form of window construction; to arrange for the easy handling of the window sashes to open and close the same; to arrange for the easy cleaning or washing of the windows and to such end to permit the window sashes to be swung or moved in such a way that the outer surface of the window or pane of glass therein may be brought inwardly so as to permit it to be cleaned from the inside of the room or place where the window is located; to simplify the construction and reduce the cost of manufacture and installation; and to secure the foregoing and other desirable results in a simple and expeditious manner.

In the accompanying drawings Figure 1 is an elevation of a window construction embodying our present invention;

Fig. 2 is a vertical section taken on line 2—2 of Fig. 1;

Fig. 3 is a similar vertical section showing the window in an operated position;

Fig. 4 is a cross section taken on line 4—4 in Fig. 2;

Fig. 5 is a view similar to Fig. 2 with the arrangement operated further than shown in Fig. 3;

Fig. 6 is a longitudinal section of a modification;

Fig. 7 is a similar view of the same in an operated condition;

Figs. 8 and 9 are cross sections taken on lines 8—8 and 9—9 respectively in Fig. 6.

Referring first to the structure shown in Figs. 1 and 4 inclusive, we show a window frame having upright members 1—1, a lower sill 2 and a top member 3. The upright members 1 are provided with longitudinally extending guideways or grooves 4 conven-

iently formed by longitudinally extending strips 5 and 6. Upper and lower sashes 7 and 8 are provided in the window frame. The upper sash 7 is provided at its upper corners with pins 9 arranged to slide in the guideways 4 and the lower sash 8 is provided with pins 10, also arranged to slide in said guideways. Arms 11 are arranged at the sides of the upper sash 7, said arms being pivoted to the window frame at 12, preferably at or near the horizontal level of the lower edge of the sash 7 when said sash is in its closed position, as shown in Fig. 2. The arms 11 are provided with lateral projections or offset ends 14, the ends of which are pivoted at 15 to the sides of the upper sash 7, the pivotal pins being preferably at or near the longitudinal middle of the sides of said sash 7. Arms 16 are provided for the lower sash 8, said arms being located at the sides of said sash and pivoted to the window frame, preferably at the pivotal point 12 where the arms 11 are pivoted. Said arms 16 are provided with lateral extensions 17, the ends of which are pivoted at 18 to the sides of the sash 8, preferably at or near the longitudinal middle of said sides. The strips 6 are provided with cut-away portions 19 and 20 (Fig. 3) to accommodate the lateral end projections 14 and 17 when the window sashes 7 and 8 are in closed position, as shown in Fig. 2. Bars or rods 21 are arranged in the grooves or guideways 4 and connected with the ends of the sashes as by means of the pins 9 and 10. Thus the corresponding ends or edges of the sashes are connected together so as to move in unison. In this way the two window sashes may be adjusted to any desired degree of opening, one or the other of said sashes being adjusted by moving it manually or otherwise; for example the lower sash 8 may be swung upwardly as shown in Fig. 3, and when this is done its pivotal or sliding connection with the window frame formed by the pins 10 will move downwardly in the grooves or guideways 4 and the lower portion of the sash will swing upwardly, as shown in Fig. 3, whereupon the upper portion of the sash 7 will also be drawn downwardly by means of the slide rods or bars 21, thereby causing said upper sash 7 to swing outwardly on the arms 11, the lower sash 8 swinging outwardly on the arms 16. This movement may be carried to such an extent as to completely reverse the sashes 7 and 8. In such case the

pins 9 will slide downwardly and the opposite edge of the sash 7 will swing upwardly so that the pins 9 will come into position about opposite the pivots 12 and the other edge of the sash will fit within the upper portion of the window frame, completely reversing the sash so that it fits snugly in the window frame in an upside down condition just as it fitted in said frame in its normal position, before the turning and reversing movement began. Similarly the sash 8 will be swung so that the pins 10 move to the bottom of the grooves or guides 4 and the other edge of the sash comes into the window frame, with the sash in a completely reversed position fitting the frame just as in normal condition except that the sash is upside down. This complete reversal is shown in Fig. 5. During this reversal movement the arms 11 and 16 merely swing out until the sashes come into substantially horizontal position, as shown by the sash 8 in Fig. 3 and then said arms swing backwardly to their normal positions, the rods 21 moving downwardly during all of this operation so that they move from their uppermost position as shown in Fig. 2, to their lowermost position, as shown in Fig. 5. This construction with its operation permits many advantages, as for example the following: The sashes may be adjusted to any desired position to secure as much or as little ventilation as desired; the sashes may be completely reversed and the window closed with the sashes in reversed position, whereby the outer sides of the window panes may be washed or cleaned from inside of the room and with the window closed, thereby preventing cold air coming into the room when the windows are being washed; during operation no part of either sash comes into the room, whereby screens, ventilating devices or other attachments may be used on the inside of the frame. The window sashes are counterbalanced by each other, the top of the upper sash tending to move downwardly and the top of the lower sash tending to move upwardly, so that the connecting rods act to counterbalance these tendencies.

Referring to the modification shown in Figs. 6 to 9 inclusive, the general arrangement is very similar but the arms 16^a for the lower sash 8 are longer than the arms 11 for the upper sash 7, instead of being of substantially the same length as in the other arrangement. Furthermore, said arms 16^a are not pivoted to the window, but are on the other hand pivoted at points 25 appreciably above the middle point 12 as shown in Fig. 7. The connecting parts or rods 21 are used in this form as in the other one. The arrangement may be operated in the same way to secure any desired adjustment of the window sashes for ventilation or other purposes, and the operation may be

continued to bring about a complete reversal of the window sashes, so that they will fit in closed positions upside down in the window frame. The difference in the length of the arms 16^a and the difference in the location of the pivotal supports for the same causes a somewhat different relative adjustment of the two window sashes 7 and 8, as compared with the adjustment secured by the other arrangement, the window sashes 75 being opened more nearly the same extent or more nearly in correspondence in the arrangement of Figs. 6 and 7 than in the other arrangement. Thus for example, when opened as shown in Fig. 7, the lower sash 8 is opened more nearly the same extent as the upper sash 7, instead of being opened as wide as shown in Fig. 3.

Changes and modifications may be made without departing from the spirit of the invention.

What we claim is:

1. The combination with a window frame, of window sashes therein, said sashes being mounted for sliding movement in said window frame and also being mounted for swinging movement about corresponding edges extending between the opposite sides of said window frame, means for connecting said corresponding edges of the window sashes together so that they will slide in unison, and means for supporting said sashes to permit them to swing about said corresponding edges and also to permit said corresponding edges to slide in the window frame, said supporting means being located near the middle of said sides of the window frame.

2. The combination with a window frame, of sashes therein, said sashes having corresponding edges provided with pivotal and sliding connections with opposite sides of the window frame, means for connecting said edges of said sashes together to slide in unison, and arms pivoted to the opposite sides of the window frame between the sashes when open, and pivotally supporting said window sashes.

3. The combination with a window frame, of sashes therein, said sashes having corresponding edges provided with pivotal and sliding connections with opposite sides of the window frame, means for connecting said edges of said sashes together to slide in unison, and arms pivoted to the opposite sides of the window frame between the sashes when open, and pivotally supporting said window sashes near the longitudinal middle of the sides of said sashes.

4. The combination with a window frame of sashes therein, said sashes having corresponding ends provided with sliding pivotal connections with the window frame, means for connecting said edges of said sashes together, and arms pivotally connected to the

- window frame outside of the closed position of the window sashes and near the middle of the window frame, said arms being pivotally connected to the sides of the window
- 5 sashes near the middle portions thereof.
5. The combination with a window frame of sashes therein, said sashes having corresponding ends provided with sliding pivotal connections with the window frame,
- 10 means for connecting said ends of said sashes together, and arms pivotally connected to the window frame outside of the closed position of the window sashes and near the middle of the window frame, said arms being pivotally connected to the sides of the window
- 15 sashes near the middle portions thereof, the arms for the upper and lower sashes being pivotally connected to the window frame at common points.
- 20 6. The combination with a window frame
- of sashes therein, said sashes having corresponding ends provided with sliding pivotal connections with the window frame, means for connecting said edges of said sashes together comprising rods 21 mounted 25 for sliding movement relatively to the window frame, and arms pivotally connected to the window frame outside of the closed position of the sashes and near the middle of the window frame, said arms being pivotally 30 connected to the sides of the window sashes near the middle portions thereof.

In witness whereof, we hereunto subscribe our names this 19th day of March, A. D., 1915.

BENJAMIN R. COLEMAN.
LEROY B. TAYLOR.
